UNITED STATES PATENT OFFICE.

SAMUEL V. KENNEDY, OF AUBURN, NEW YORK, ASSIGNOR TO D. M. OSBORNE & COMPANY, OF AUBURN, NEW YORK, A CORPORATION OF NEW YORK.

MOWING-MACHINE.

SPECIFICATION forming part of Letters Patent No. 716,430, dated December 23, 1902.

Application filed May 27, 1901. Serial No. 61,989. (No model.)

To all whom it may concern:

Be it known that I, SAMUEL V. KENNEDY, of Auburn, in the county of Cayuga and State of New York, have invented a certain new and useful Mowing-Machine, of which the following is a specification.

My invention has for its object the production of particularly simple, economical, and efficient connections between the coupling-frame and the finger-bar of a mowing-machine; and it consists in the combination, construction, and arrangement of the contiguous portions of said coupling-frame and finger-bar and the connections between the same, as hereinafter fully described, and pointed out in the claims.

In describing this invention reference is had to the accompanying drawings, forming part of this specification, in which like letters indicate corresponding parts in all the views.

Figure 1 is a top plan of a mowing-machine embodying my invention, a portion of the pole being broken away. Fig. 2 is a front elevation, partly in section, of a portion of said machine. Fig. 3 is an enlarged top plan of contiguous portions of the cutter and finger-bars and the coupling-frame operatively connected together. Figs. 4 and 5 are vertical sectional views taken, respectively, on lines 44 and 55, Fig. 1.

A B C represent, respectively, the cutter-bar, the finger-bar, and the coupling-frame of my mowing-machine, all of which parts may be of any suitable form, size, and construction. Said finger-bar B and coupling-frame C are provided, respectively, with an inner shoe b and a yoke D, which so far as this invention is concerned form, essentially, parts of the finger-bar and the coupling-frame. The main body of the coupling-frame C is preferably provided with a substantially horizontal pivotal portion c, Fig. 4, extending parallel with the line of draft, and the coupling-frame bar c' is connected at one extremity to said main body by a coupling member c², having its rear end provided with a tubular part journaled on the pivotal portion c and its front end provided with a bearing c³, which is arranged at substantially right angles with the pivotal portion c and supports the contiguous extremity of the bar c'. The other extremity

of the frame-bar c' is provided with a fixed lateral extension c⁴, Figs. 1, 3, and 5, having an upwardly-extending pivotal portion c⁵, Fig. 5. The described connection between the main body of the frame C and the coupling-bar c' thereof is particularly suitable for use with the remaining parts of my mowing-machine; but said connection forms no part of my present invention.

One end of the yoke D is provided with depending ears d, arranged one in advance of the other and pivoted to the finger-bar B, or, more strictly speaking, to its inner shoe b, by substantially horizontal pivots d', and the other end of the yoke D is provided with slots d², arranged one in advance of the other. The intermediate portion of the yoke D is formed with a socket d³ in its lower face, Fig. 5, for receiving the pivotal portion c⁵ of the lateral extension c⁴ of the coupling-frame bar c' and is pivoted to said extension by the socket d³ and the pivotal portion c⁵ and by a suitable vertical pivot d⁴, passed through the intermediate portion of the yoke D and said pivotal portion c⁵. Said yoke D is rigidly secured to the coupling-frame bar by means here illustrated as consisting of a substantially U-shaped fastening member d⁵, having its intermediate portion engaged with the lower surface of the bar c' and its opposite branches engaged with opposite sides of said bar, passed through the slots d² and provided with nuts d⁶, bearing upon the upper face of the yoke for holding said fastening member in its adjusted position.

In the use of my mowing-machine whenever it is desired to force the outer end of the finger-bar forwardly or backwardly the nuts d⁶ are loosened and the yoke D is rocked upon its substantially vertical pivotal connection to the coupling-frame until the finger-bar is sufficiently adjusted, whereupon the nuts d⁶ are firmly clamped against the yoke and the finger-bar is held in its adjusted position.

The construction and operation of my mowing-machine will now be readily understood upon reference to the foregoing description and the accompanying drawings, and it will be particularly noted that more or less change may be made in the component parts thereof

without departing from the spirit of my invention.

Having thus fully described my invention, what I claim as new, and desire to secure by 5 Letters Patent, is—

1. In a mowing-machine, the combination of a finger-bar and a frame-bar having a fixed lateral extension; with a yoke pivoted to the finger-bar by a substantially horizontal pivot 10 and pivoted to the lateral extension of the frame-bar by a substantially vertical pivot, and means for rigidly securing the frame-bar to the yoke, substantially as and for the purpose specified.
- 15 2. In a mowing-machine, the combination of a finger-bar and a frame-bar having a fixed lateral extension; with a yoke having one end provided with depending ears pivoted to the finger-bar by substantially horizontal pivots, 20 and its intermediate portion pivoted to the lateral extension of the frame-bar by a substantially vertical pivot, and means for rigidly securing the frame-bar to the other end of the yoke, substantially as and for the purpose 25 described.
3. In a mowing-machine, the combination of a finger-bar and a frame-bar having a lateral extension; with a yoke having one end provided with depending ears pivoted to the finger-bar by substantially horizontal pivots, its intermediate portion pivoted to the lateral extension of the frame-bar by a substantially vertical pivot, and its other end provided with slots arranged one in advance of the other, 30 and a substantially U-shaped fastening member having its intermediate portion engaged with the frame-bar and its opposite branches passed through said slots and provided with means for clamping the frame-bar to the yoke, 35 substantially as and for the purpose specified.
4. In a mowing-machine, the combination of a finger-bar and a frame-bar having a fixed lateral extension provided with a substantially vertical pivotal portion; with a yoke pivoted to the finger-bar by a substantially horizontal pivot and provided with a socket 40 for receiving the substantially vertical pivotal portion of said lateral extension, and 45 means for rigidly securing the frame-bar to the yoke, substantially as and for the purpose set forth.
5. In a mowing-machine, the combination of a finger-bar and a frame-bar having a fixed

lateral extension provided with a substantially vertical pivotal portion; with a yoke having one end provided with depending ears pivoted to the finger-bar by substantially horizontal pivots and its intermediate portion provided with a socket for receiving the substantially vertical pivotal portion of said lateral extension, and means for rigidly securing the frame-bar to the other end of the yoke, substantially as and for the purpose described. 60

65 6. In a mowing-machine, the combination of a finger-bar and a frame-bar having a fixed lateral extension provided with a substantially vertical pivotal portion; with a yoke pivoted to the finger-bar by a substantially horizontal pivot and provided with a socket for receiving the substantially vertical pivotal portion of said lateral extension, a substantially vertical pivot passed through the yoke and the pivotal portion of said lateral extension, and means for rigidly securing the frame-bar to the yoke, substantially as and for the purpose specified. 70

75 7. In a mowing-machine, the combination of a finger-bar and a frame-bar having a lateral extension provided with a substantially vertical pivotal portion; with a yoke having one end provided with depending ears pivoted to the finger-bar by substantially horizontal pivots, its intermediate portion provided with a 80 socket in its lower face for receiving the substantially vertical pivotal portion of said lateral extension, and its other end provided with slots arranged one in advance of the other, a substantially vertical pivot passed 85 through the intermediate portion of the yoke and the pivotal portion of said lateral extension, and a substantially U-shaped fastening member having its intermediate portion engaged with the frame-bar, and its opposite 90 branches passed through the slots in the yoke and provided with means for rigidly securing the frame-bar to the yoke, substantially as and for the purpose set forth. 95

100 In testimony whereof I have hereunto signed my name, in the presence of two attesting witnesses, at Auburn, in the county of Cayuga, in the State of New York, this 14th day of May, 1901.

SAMUEL V. KENNEDY.
